Peter M. Boesen, ATTORNEY

UNITED STATES PATENT OFFICE

2,145,738

BROOM SWEEPER

August Sandberg, New York, N. Y.

Application November 4, 1937, Serial No. 172,655

1 Claim. (Cl. 15—82)

The present invention relates to new and useful improvements in broom sweepers, and it has for its object to provide an automatically adjustable broom sweeper, which may be manipulated with great ease, and applied and turned in different directions in order to sweep places and corners to which no access can normally be had with the sweepers now in use.

Furthermore, the construction of my said device is to the effect that the broom proper will always retain its full sweeping capacity, even if the bristles of the broom become worn and shortened, as the special construction of my device takes this feature into consideration, as will hereinafter appear.

As the construction of my device is comparatively simple, the cost of manufacturing should be proportionately low.

With the above and other objects in view, this invention consists of the novel features of construction, combination, and arrangement of parts, hereinafter fully described, claimed and illustrated in the accompanying drawings forming part of this application, and in which similar characters of reference indicate corresponding parts in all views, and in which:

Figure 1 is a perspective view of an automatically adjustable broom sweeper.

Figure 2 is an exploded view of the invention, as shown in Figure 1, and illustrating the major parts of my device.

Figure 3 is a side elevational view, showing the inside of one of the large wheels, with the brush member broken off, and showing also the brush proper provided with new bristles, indicating at the same time the driving gear and the relative position of the latter to the axle drive, said relative position depending upon the length of the bristles.

Figure 4 is a front elevational view of the inner side of one of the larger, or front wheels, showing the bristles of a brush member worn down, and thereby affecting the relative position of the drive gear with respect to the drive shaft, and showing also one of the frames for holding the driving member.

Figure 5 is a front elevational view, showing the inner part of a front wheel, i. e., one of the larger wheels, ready for assembling.

Figure 6 is an elevational view, showing the driving shaft with gears attached thereto.

Figure 7 is a front elevational view, showing the brush gear.

Figure 8 is a side elevational view of the lower gear, as shown in Figure 6,

Figure 9 is a top plan view of the gear shown in Figure 8.

Figure 10 is a transverse sectional view of the bottom part of the axle, shown in Figure 6.

Figure 11 is an elevational view of the drive shaft, as seen also in Figure 6, indicating more clearly the recess for guiding the up and down movement of the drive gear, shown in the Figures 8 and 9.

Figure 12 is a top view of an enclosing member 10 for securing the brush to the brush shaft.

Figure 13 is a transverse side elevational view of the member shown in Figure 12.

Figure 14 is a front elevational view showing the parts illustrated in the Figures 8, 10 and 12 assembled, and attached to the brush member.

Referring more particularly to the drawings, 20 indicates a frame, or carriage, adapted to receive therein a brush sweeper with means for actuating the latter; said frame has a cover member 21 attached to the rear side thereof to protect the operator from dirt and dust.

Said carriage 20 is secured to a cross-bar 22 by means of bolts 23 inserted through the openings 24 and 24', respectively; these parts 20 and 22 are in turn pivotally secured to the operating means 5 by means of a bolt 26 inserted through the openings 27 and 27' in the members 22 and 25, respectively.

The operating means comprises the handle 30 bars 28, and the steering bar 29, which latter is integral with the carriage frame 20, and thus capable of moving the carriage in any direction. To facilitate the operation, the said steering bar may be secured in adjusted position by means 35 of a bolt 30 through any of the openings 31 in the cross-bar 22.

The carriage frame has secured to it the small wheels 33, as shown.

The brush sweeper proper comprises an axle 40 34 with bristles 35 secured to the latter; as shown in Figure 2. Said bristles 35 are shown as new in Figure 3, and in a partly worn down condition in Figure 4, as indicated by the numeral 35'.

Within the carriage are mounted two large 45 wheels 36.

Frames 37 are secured to the carriage 20, and connected to each other by a cross bar 41; said frames are adapted to support the gear arrangement hereinafter described.

Each one of the large wheels 36 has upon its inner side securely attached thereto a gear 38, as shown especially in the Figures 4 and 5.

A short center axle 39 is inserted through each of the wheels 36, as shown especially in Figure 3;

each axle 39 supports a frame member 40 and one of the depending side members of the carriage 20, as shown in the Figures 3 and 5.

In each of the frame members 37 is, as shown in Figure 6, pivotally mounted a vertical axle 42. Upon said axle 42 is securely attached a gear 43 adapted to mesh with the gear 38, as shown in Figure 3. Upon said axle 42 is further mounted another gear 44 adapted to move up and down upon said axle, this gear 44 being guided in its said movement by a projection 45 formed upon said gear 44; said projection being adapted to slide in a guiding recess 46 formed in the vertical axle 42. The gear 44 is upon its depending part 47 and upon the outer surface thereof formed with an annular groove 48, as shown in Figure 8.

Upon the axle 42 is further pivotally mounted a block member 49, as shown in Figure 6, and more especially in Figure 10; said block member 20 is in its upper part formed with a bore 50, which is adapted to receive therein the depending part 41 of the gear 44; said block member has mounted in the sides thereof screws 51, which are adapted to loosely engage the recess 48 in the depending portion 47. The block member 49 has a projecting axle 52 adapted to receive a gear member 53 thereon, said gear member being shown separately in Figure 7, and attached in Figure 3; this gear 53 is adapted to mesh with the gear 44, and turns upon the axle 52, the gear being held upon said axle by means of a nut 54. To the gear member 53 is securely attached a casing 55, which is shown separately in the Figures 12 and 13, and attached in the Figures 3 and 14. The casings are attached to each end of the brush axle, by means of screws 56, and to the gear 53, as shown in Figure 14.

The frames 37 are securely attached to the frame members of the carriage 20 by rivets 59, as shown in Figure 3, and to the frame 40, as shown in Figure 3, also.

The axle 42 is turnably mounted in the frames by means of the screws 60 and 60'.

It will be apparent that the gear 44 and the block member 49, which, as described, are con-

nected to the brush, will assume a position upon the axle 42, depending upon the height of the brush bristles, as may clearly be noted by comparing the position of the brush, as shown in the Figures 3 and 4.

It is obvious that changes may be made in the form, construction and arrangement of the several parts, as shown, within the scope of the appended claim, without departing from the spirit of the invention, and I do not therefore 10 wish to limit myself to the exact construction and arrangement shown and described herein.

What I claim as new, and desire to secure by Letters Patent of the United States, is:

In a device of the class described, a carriage 15 structure having two side members, a large wheel arranged inside of each of the latter, and a short axle securing the side members to said wheels, respectively, a gear fixedly arranged upon the inner side of each of said wheels, frames disposed 20 within the side members and a cross bar connecting said frames together, a vertical axle being formed with a vertical recess therein and pivotally mounted in each of said frames, a gear fixedly attached to said vertical axle and adapted to 25 mesh with the gear upon the inner side of said wheel, a lower gear mounted upon said vertical axle and adapted to slide upon the latter, said lower gear having a projection thereon adapted to slide in the vertical recess of the axle, the lower gear being made with a tubular depending portion formed with an annular recess therein, a block member slideably mounted on the axle beneath said lower gear, said block member being formed with a bore adapted to receive therein 30 the depending portion of said lower gear, a stud mounted in the side of the block member and made to loosely engage said annular recess, a short horizontal axle integral with the block member, a gear mounted upon said latter axle 35 and adapted to mesh with the aforesaid lower gear and a brush drivingly connected to the latter gear.

AUGUST SANDBERG.
